UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING-MACHINE.

1,330,878.

Specification of Letters Patent.

Patented Feb. 17, 1920.

Application filed May 29, 1918. Serial No. 237,215.

To all whom it may concern:

Be it known that I, ALFRED G. F. KUROWSKI, a subject of the Emperor of Germany, but having taken out preliminary 5 United States naturalization papers, residing in Brooklyn borough, in the county of Kings, city and State of New York, have invented certain new and useful Improvements in Typewriting-Machines, of which 10 the following is a specification.

My invention relates to tabulating mechanism, and particularly to that type usually employed in the Underwood typewriter machine, in which adjustable stops carried by 15 a rack adjacent the carriage of the machine determine the positions of columns typed upon the paper; said rack being usually operated by a key to carry the stops into the path of a lug on the carriage, so that the 20 carriage will be arrested in proper position.

In tabulating mechanism of the general type or kind above referred to, the tabulator stops, which determine the positions of the columns, are commonly located back of 25 and below the carriage of the machine, and the setting of the stops is therefore a matter of inconvenience, as the operator has to reach over and down back of the carriage to get at the tabulating mechanism.

30 The principal feature of my invention is the provision of tabulating mechanism in which the tabulator stops and scale are carried by an auxiliary supporting member or frame movable with the rack above referred 35 to, and which auxiliary supporting member is movable in such a way as to bring the tabulator stops and scale into accessible positions, so that the stops may be readily set; suitable means being provided for locking 40 the parts when the tabulating mechanism is in its operative position.

Other features and advantages will hereinafter appear.

In the accompanying drawings,

45 Figure 1 is a front view illustrating my improved tabulator stop mechanism in the position into which it is moved when the stops are to be set, together with so much of a typewriting machine as is necessary in 50 order to show its application thereto.

Fig. 2 is a similar view, showing the device and machine in end elevation, with the

movable stop-carrying member swung down and locked in operative position.

Fig. 3 is a rear view showing certain details of construction of my invention.

Referring to the drawings, the reference numeral 5 designates an oscillating shaft or rod located adjacent the carriage and extending longitudinally of the typewriting 60 machine shown conventionally in the several views, and the ends of which are pivotally supported in the frame of the machine at 6, the said rod being operated through an arm 7 carried thereby and by 65 means of a vertically-movable operating member 8 pivotally connected with the free end of the arm 7 at 9; the said operating member being operated by suitable tabulating keys in or disposed adjacent the keyboard of the machine. The bar or shaft 5 carries also an arm 10 the free end of which is operatively connected with a lever 11 pivotally supported at 12, and the free end of which lever carries a roller 13 which runs 75 in engagement with the pivotally-supported rack 14, which rack in turn engages the pinion 15 rotating with the ratchet 16 of the escapement mechanism; whereby, as the operating member 8 is moved downward 80 and an angular movement imparted to the rod 5, the rack 14 will be moved upward and out of engagement with the pinion 15, thus permitting the rack and the carriage which carries the same to move freely longitudinally of the machine and under the influence of its operating spring or other device provided for moving it, until its onward movement is arrested by the engagement of a lug 17 carried by the carriage 90 with a stop carried by the tabulator stop-carrying device or mechanism to which my invention relates, as will hereinafter appear.

The mechanism for releasing the carriage is illustrated in a more or less conventional 95 manner, and the form thereof referred to is for illustrative purposes only and for the purpose of disclosing the relation between my invention and the tabulating mechanism of a typewriting machine; my invention as 100 disclosed and claimed in this present application being in no way concerned with the particular form of mechanism employed to effect the release of the carriage as a step

or operation involved in the use of the tabulating mechanism.

The oscillating shaft or bar 5 carries two arms 18 located one at each end thereof, and which arms partake of the angular movement of the shaft; the bar and arms forming a movable supporting member adapted to support a tabulating stop and to move the same into and out of the path of movement of the lug 17, as above explained. The arms 18 in turn carry and serve as a support for a swinging tabulator-stop-carrying member or frame, the same being pivotally connected with the upper ends of the arms 18, at 19, and thus movable relatively to the movable supporting member formed by the rod 5 and the arms 18.

The stop-carrying-frame or member may be variously constructed, according to the choice of the manufacturer, having in view the matters of convenience in manufacture and low cost; but, as illustrated, the same comprises a longitudinally-extending bar 20, and laterally-extending arms 21 located one at each end thereof; and the free ends of which arms are connected by a longitudinally-extending bar or rod 22 which serves as a support for and along which the tabulator stops 23, as many being employed as may be deemed necessary or desirable, are movable, in order to secure the proper and desired location of the columns of figures upon the printed sheet, as will be appreciated.

35 The reference numeral 24 designates a rack extending longitudinally of the tabulator-stop-carrying frame and the ends of which are secured to the side arms 21 thereof, and 25 designates a graduated scale carried by the said frame and secured to the rack 24 in the embodiment of my invention illustrated, which scale is graduated to correspond with the main line-spacing scale of the machine and is used by the operator in 45 setting the stops to determine the proper location of the columns, as will be understood. The tabulator stops 23 are shown as provided each with a pointer 26; and they are movable angularly upon the supporting bar 50 or rod 22 whereby they are carried, in order that a tooth 27 provided at the free end of each may be swung out of engagement with the rack 24, preparatory to moving the stop along the rod; the rack and tooth 27 serving 55 as means for locking the stop in whatever position it may be placed. The stops 23 are also provided each with a lug 28 which, when the tabulating mechanism is operated to effect the stopping of the carriage in 60 proper position for printing in a column, are moved into and lie in the path of and are engaged by the lug 17 carried by the carriage, thus arresting the movement of the carriage; the said lug 28 being moved into 65 the path of the lug 17 by means of a tabu-

lator release-key operating through the operating member 8, arm 7, oscillating bar 5 and arms 18 carried thereby; and which arms in turn are connected with and support the stop-carrying-frame carried by and movable relatively to the supporting member formed by the bar 5 and arms 18, as will be understood.

The swinging tabulator-stop-carrying-frame is locked in its lowermost position by 75 any suitable locking means, such, for example, as the spring-operated catch or latch 29 pivotally connected with an arm 30 extending from one of the side arms 21 of the said frame, which latch engages a tooth 31 upon the adjacent arm 18 carried by the oscillating bar 5; the upward swinging movement of the said frame is arrested by contact between a projecting lug or pin 32 also carried by an arm 21, and an arm 18; and the tabulator stop mechanism as a whole is kept in its rearward and inoperative position with the lugs 28 of the stops 23 out of the path of travel of the lug 17 upon the carriage by means of a spring 33 secured to and carried 90 by the bar 5, and the free end of which contacts with the frame of the machine.

The movable frame member 21, whereby the rack 24 and bar 22, which carries the adjustable stops 23, are supported, is illustrated as in the form of a casting, in which the transverse bar 20 and arms 21 are formed integral with one another.

Referring now to the drawings, it will be appreciated that if the stops 23 were supported in fixed relation to the oscillating bar or rod 5, as has heretofore commonly been the case, then the operator in order to set the stops would have to reach over and back of the paper-table 34, or step to the 100 end or to the rear thereof, since the paper-table extends considerably to the rear of the shaft 22 on which the stops are journaled; the setting of the stops being an awkward operation and one involving considerable 105 inconvenience, and an operation which, because of the circumstances enumerated, is liable to be improperly performed, unless careful attention is given to the matter. In my improved tabulating mechanism, 110 however, when the operator has occasion to set the tabulator stops the latch or catch 29 is operated to release the swinging stop-carrying frame; whereupon the same and the stops carried thereby may be swung into 115 the elevated position in which the parts are illustrated in full lines in Fig. 1 and in dotted lines in Fig. 2; thus bringing the tabulator stops and the scale for indicating their 120 positions into plain sight, and into a position just back of and slightly above the carriage of the typewriter; in which position the adjusting of the stops can be readily done with the least inconvenience and liability of error; after which the stop carry- 125 130

ing member or frame is swung down and into its operative position, and locked therein by the latch as will be appreciated, the latch being swung to effective position by 5 the spring 35 coiled about its mounting.

Variations may be resorted to within the scope of the invention, and portions of the improvements may be used without others.

Having thus described my invention, I 10 claim:

1. In a tabulating device for typewriters, a movable supporting member located adjacent the carriage and paper-table of a typewriter, and means for moving said member to thereby move a stop partaking of the movement thereof into and out of the path of movement of a lug carried by the typewriter carriage; arms extending upwardly and rearwardly from said supporting member; a tabulator stop carrying member comprising arms pivoted at the upper ends of said first arms and having a bar normally adjacent said lug; means for holding said bar in its normal position, and adapted to 20 be released to enable the bar to carry the stops above the paper-table; and an adjustable stop carried by said stop carrying member, the said stop partaking of the movement of said movable supporting member, as aforesaid.
2. In a front-strike typewriting machine having a carriage and a paper-table thereon at the back of the carriage; an adjustable stop; a swinging frame comprising up- 30 standing arms and a cross-bar whereby said stop is carried at the bottom of the arms; a cross-bar connecting the upper ends of said arms; means pivoted on the body of the typewriter, comprising upstanding arms having pivots at their upper ends to support the swinging frame at its upper cross-bar, a lug on one arm adapted to arrest the frame, said pivots and lug so adjusted that when the frame is swung up the stop stands 40 above the paper-table so that the stop may be adjusted; a latch normally and positively holding said frame swung down and in toward the paper-table; and a carrier for the frame adapted to carry the stop thereon 45 into the path of a lug on the typewriter carriage.
3. In a front-strike typewriting machine having a carriage and a paper-table thereon at the back of the carriage; a lug on the 55 carriage beneath the table; an adjustable stop beneath the table and normally out of the path of the lug; a pivoted device on which said stop is carried, adapted to swing it to enable it to strike the lug, upwardly
- 60 and rearwardly extending arms on said device; a bar on which said stop is adjustably carried and journaled; upwardly and rearwardly extending arms on which the bar is fast; pivots at the top of said first arms 65 on which said second arms are journaled; a

latch for holding said stop-bar against swinging; and a rack bar connecting said second arms, adapted to be engaged by said stop.

4. In a front-strike typewriting machine 70 having a carriage and a paper-table thereon at the back of the carriage; a lug on the carriage beneath the table; an adjustable stop beneath the table and normally out of the path of the lug; a pivoted device on which 75 said stop is carried, adapted to swing it to enable it to strike the lug; upwardly and rearwardly extending arms on said device; a bar on which said stop is adjustably carried and journaled; upwardly and rearwardly 80 extending arms of which the bar is fast; pivots at the top of said first arms on which said second arms are journaled; a lug on one arm adapted to strike the adjacent arm of the other set, to support the swung-up 85 stop-bar above the table; a latch for holding said stop-bar against swinging; and a rack bar connecting said second arms, adapted to be engaged by said stop.

5. In a front-strike typewriting machine 90 having a carriage and a paper-table thereon at the back of the carriage; a lug on the carriage beneath the table; an adjustable stop beneath the table and normally out of the path of the lug; a pivoted device on which 95 said stop is carried, adapted to swing it to enable it to strike the lug; upwardly and rearwardly extending arms on said device; a bar on which said stop is adjustably carried and journaled; upwardly and rear- 100 wardly extending arms on which the bar is fast; pivots at the top of said first arms on which said second arms are journaled; a lug on one arm adapted to strike the adjacent arm of the other set, to support the 105 swung-up stop-bar above the table; a latch for holding said stop-bar against swinging; a rack bar connecting said second arms, 110 adapted to be engaged by said stop; and a scale-plate on the rack bar brought to the front by the up-swinging of the stop-bar and adapted to coöperate with a pointer on a stop to indicate its position.

6. In a tabulating device for typewriters, an adjustable stop; a swinging pivoted 115 supported frame whereby said stop is carried; means for supporting said frame adjacent the carriage of a typewriter; means for moving said supporting means to thereby move said stop into and out of the path 120 of movement of a lug carried by the typewriter carriage; and means for detachably securing said swinging frame to said supporting means.

7. In a tabulating device for typewriters, 125 a pivotally supported oscillating shaft and means for operating the same; arms carried by said shaft and partaking of the movement thereof; a tabulator stop carrying frame carried by said arms and movable relatively 130

thereto; plurality of adjustable stops carried by said frame and movable therewith into and out of the path of movement of a lug carried by the carriage of the type-
writer; and a latch carried by said tabulator stop carrying frame and adapted to secure the same in a fixed position relative to said oscillating shaft.

8. In a tabulating device for typewriters,
10 a pivotally supported oscillating shaft and means for operating the same; arms carried by said shaft and partaking of the movement thereof; a swinging tabulator stop carrying

frame pivotally connected with the free ends of said arms; a plurality of adjustable stops carried by said frame and movable therewith into and out of the path of movement of a lug carried by the carriage of the type-
writer; and a latch carried by said swinging frame and adapted to engage a tooth carried by one of the arms carried by said oscillating shaft.

ALFRED G. F. KUROWSKI.
